DESIGN FOR A DRAWER PULL

Earl M. Borchers, Rockford, Ill., assignor to
American Cabinet Hardware Corporation,
Rockford, Illinois, Rockford, Ill., a corporation
of Illinois

Application August 8, 1945, Serial No. 121,313

Term of patent 7 years

(Cl. D10—8)

To all whom it may concern:

Be it known that I, Earl M. Borchers, a citizen
of the United States, residing at Rockford, in
the county of Winnebago and State of Illinois,
have invented a new, original, and ornamental
Design for a Drawer Pull, of which the following
is a specification, reference being had to the
accompanying drawing, forming a part thereof.

Figure 1 is a plan view of a drawer pull em-
bodying my new design.

Fig. 2 is a front elevational view of the same.

Fig. 3 is an end elevational view.

I claim:

The ornamental design for a drawer pull, sub-
stantially as shown.

EARL M. BORCHERS.
